METHOD AND APPARATUS FOR STRAIGHT-
ENING SHEET MATERIALFriedrich K. Mäussnest, Woodside, N. Y., assignor
to Hedwig Mäussnest, Woodside, N. Y.

Application March 27, 1934, Serial No. 717,610

35 Claims. (Cl. 153—54)

This invention relates in general to a method of, and apparatus for, flattening or straightening sheet, strip and plate material in machines of the roller leveler type, but more specifically though not limited, to machines of this character which employ comparatively small diameter straightening or sheet-engaging rolls, so as to obtain superior working effects on the sheet to be flattened.

10 The reason for passing sheets through straightening machines or so-called roller levelers is that the sheets coming from the rolling mill are not flat and mostly show an increased length of the edge areas in relation to the middle area of the sheet, or vice versa, which distorted condition is called the mill shape of the sheets. In order to render these distorted sheets into a flat condition as required for commercial purposes, it is essential to stretch same along their short area or areas.

15 The function of small diameter straightening rolls engaging a sheet is to flex the material of the sheet by successively and alternately subjecting the same part of the sheet to compression and tension stresses; for this reason it is evident that the smaller the diameter of the straightening rolls, the more effective the leveling action will be.

20 The contact surfaces of the straightening rolls produce during their rotation a kneading effect 30 within the grain structure of the sheet, subjecting the same to stresses considerably beyond its yield point by creating a series of transverse bends or corrugations. This action eliminates the internal stresses in the sheet, rendering the same in a state of cold plasticity. This condition favors 35 flattening the sheet throughout its entire length and width by stretching the short area or areas of the sheet.

40 To apply small diameter straightening rolls introduces however certain difficulties which not only manifest themselves in an undesirable wear on the working parts and elements of the machine, but also in an undesired longitudinal deflection of the rolls which prevents said rolls from maintaining that contour during the straightening process which would result in the most effective leveling action.

45 The sheet-engaging rolls are not only supported in bearings at their ends, but they are also reinforced on so-called supporting rolls which are located along and in staggered order to the straightening rolls. Whenever the latter are to 50 straighten a sheet, the pressure to be given at

the desired location of the sheet may be adjusted by means of such supporting rolls.

5 However, the results so far obtained are still lacking the desirable flexibility of adjustment of the straightening rolls and the positive and unyielding support of the rolls in their flexed condition which would lead toward an effective, durable, and efficient machine, employing the smallest feasible roll diameters without sacrificing rigidity as is required in the metal industries.

10 Of the several methods known to the trade that of the V or inverted V formation of relatively displaceable supporting rolls has given the most preferable results over the others. In this method of sustaining the straightening rolls, 15 however, the outer edges and the inner edges of pairs of supporting rolls form a respective V or inverted V shape which will be in contact with the flexed straightening rolls, resulting in a support of the latter on certain points only, but not

20 on the desirable total length of the supporting rolls. The flexed working contour of the straightening rolls should preferably resemble either a concave or convex curve. Its selection depends 25 on the distorted condition of the sheet to be flattened.

25 The journals of the rolls are very sensitive for 30 the reason that the diameter of these rolls should be as small as possible in proportion to the thickness of the sheets to be straightened. On account of the flexing of the rolls, the bearings of same are subjected to uneven pressures when bearings with fixed locations are employed. This therefore results in excessive wear and a tendency to break the rolls.

35 The formation of the deflected roll contour 40 imposes certain stresses on the small diameter rolls and experience shows that the straightening rolls assume a certain permanent convex contour after a given length of operation which interferes with the adjustment of the proper roll contour, especially as far as adjusting such rolls into concave contours is concerned. This in turn unfavorably affects the straightening results.

45 The time required for actually passing a sheet 50 of 10 feet length through the rolls of a leveler which has a delivery speed of 60 feet a minute is 10 seconds. The time elapsed between the adjustment of the machine for a distorted sheet and the readjustment for a distorted sheet of different mill shape is frequently one or more minutes when sheets of differing distortions are subsequently flattened. If batches of sheets with the same mill shape are straightened, the straightening rolls may remain for instance in 55

a convex contour for hours or maybe even days, resulting in a permanent distortion of the rolls, while only a fraction of this time is usefully employed for actually flattening sheets. It is therefore desirable to eliminate this defect.

One of the main objects of my invention is to provide means whereby both the straightening rolls and the supporting rolls are quickly and accurately adjustable relative to each other to 10 deflect the rolls into any contemplated convex or concave contour depending on the distorted condition of the sheet to be straightened.

Another object is to reinforce the straightening rolls over a substantial part of their length 15 during operation on substantially the entire length of the supporting rolls which will have a contour similar to the working curve required by the other rolls.

It is also an object of my invention to cause 20 a sheet to deflect the rolls into a predetermined working contour during the time said sheet is passing through the rolls.

Furthermore it is an object to provide bearings on straightening rolls and/or supporting 25 rolls which permit the rolls to remain in their straight and unstrained condition until such time as a sheet is actually passed through the rolls.

Another object of my invention is to provide 30 in combination with such bearings, means to lock the movement of the same if desired.

These and other objects which will be pointed out in the specifications and especially in the 35 claims to follow, I attain by means of my invention disclosed in the drawings, wherein:

35 Fig. 1 is a front view of a sheet straightening machine in section along line 1—1 Fig. 2.

Fig. 2 is a side view of the machine shown in Fig. 1.

Fig. 3 illustrates a partial sectional top view 40 of rolls and supports on line 3—3 Fig. 2.

Fig. 4 is a partial sectional top view of secondary rolls in their bearings on line 4—4 Fig. 2.

Fig. 5 is a sectional side view of the lower 45 part of the straightening machine on line 5—5 Fig. 1.

Fig. 6 is a sectional front view of a modified form of the lower part of the straightening machine shown in Fig. 1.

Fig. 7 illustrates a sectional front view of the 50 lower part of a straightening machine similar to Fig. 1 showing however a different arrangement for adjusting the rolls.

Fig. 8 shows a sectional top view of part of a roll adjustment on line 8—8 Fig. 7.

Fig. 9 illustrates a sectional front view of the 55 lower part of a straightening machine with divided supporting rolls.

Fig. 10 shows a similar view as Fig. 9, depicting a modified form of the roll adjustment.

Fig. 11 illustrates a sectional side view of the 60 machine of Fig. 9 on line 11—11.

Fig. 12 shows a side view of a modified arrangement of bearing blocks, partly in section.

Fig. 13 illustrates a sectional front view of the 65 bearing block of Fig. 12 on line 13—13.

Figs. 14, 15, 16, and 17 illustrate in diagrammatic form convex and concave roll displacements possible by means of the constructions shown in Figs. 1 and 7.

70 Figs. 18 and 19 illustrate diagrammatically one of the roll displacements possible by means of the construction in Fig. 6.

Figs. 20 and 21 show in diagrammatic form 75 one of the roll displacements possible by means of the construction in Fig. 9.

Figs. 22 and 23 illustrate diagrammatically one of the roll displacements possible by means of design in Fig. 10.

Fig. 24 shows a perspective view of one upper and two lower, deflected straightening rolls to illustrate the plastic deformation of the sheet passing through said rolls.

In referring to Figs. 1 to 5, the machine illustrated comprises a lower base section 1 and an upper detachable section 2, both of which may 10 represent the main body portions of a conventional type sheet or plate straightening machine. To base 3 of lower section 1 are secured in a suitable manner two walled uprights 4, which serve 15 the purpose to guide at their outer ends two vertically displaceable bearing supports or pillow-blocks 5. These supports retain each a bearing or bearing body 6 which is located on the top surface of each support. The contacting surfaces of supports 5 and bearing bodies 6 are curvilinear in a 20 direction to the length of the lower sheet-flexing elements or sheet-engaging rolls 7.

The sheet-engaging rolls or straightening rolls 7 have their bearing ends 8 located within bearing bodies 6 and are freely rotatable therein. 25 The curvilinear bearing surfaces serve the purpose to permit bearing bodies 6 to change their location whenever rolls 7 are caused to change their contour and are to assume a flexed condition as shown for instance in Fig. 15. This will 30 therefore result in a more even distribution of the frictional forces on bearing ends 8 of each roll. Furthermore, bearing bodies 6 may be lifted away from pillow-blocks 5 when adjusting the rolls for 35 a convex formation (Fig. 16). Bearing supports 5 are guided between shoulders 9 of uprights 4 and suitable gibs or plates 10 are fastened to the 40 uprights.

Underneath the lower straightening rolls 7 and 45 between each pair thereof are located supporting instrumentalities or supporting rolls 11, which may be of substantially the same diameter as the other rolls. Rolls 11, which are shorter than the others, are supported at their ends in bearings or bearing bodies 12 which rest on a pair of secondary uprights 13 secured to the base 3 in any 50 suitable manner.

The supporting surfaces of both bearing bodies 12 and uprights 13 have a curvilinear contour 55 similar to those previously described. The formation of these surfaces is also for the purpose to permit the supporting rolls 11 to flex in longitudinal direction without exerting undue strain on the bearing ends of the rolls as well as the inner surfaces of the bearing bodies 12.

Underneath and between each pair of supporting rolls 11 is located a pivot roll 15 of comparatively short length, but substantially large diameter. Each pivot roll is supported on its bearing ends 16 in a supporting yoke 17, movable 60 with the pivot rolls in vertical direction and guided in reinforcements of inner walls 18 of uprights 4, Figs. 4 and 5.

The weight of yoke 17 and its pivot rolls is carried by two vertically displaced adjusting screws 65 19, engaging hubs 20 of the yoke. These screws are rotatably mounted with their shanks or extensions 21 in bosses 22 which form a part of and extend below the top surface of base 3. Screws 19 are prevented from moving in either vertical 70 direction by means of collars 23 at the lower end and worm-wheels 24 resting on the top surface of base 3 and located below the threaded part of the screw. Both worm-wheels are secured tight to their respective screws 19 for the reason that 75

their lower surfaces carry the weight and the pressure exerted on the pivot rolls. Between the worm-wheels and in engagement with same is a worm 25 secured to a shaft 26. When turning this shaft, the rotating screws will thus either raise or lower the yoke with its pivot rolls 15; the latter may also be referred to as reinforcing elements. In using only one worm for the operation of two worm-wheels, it is evident that one of the screws 19 must have a thread directed opposite to that of the other. Shaft 26, which extends throughout the whole length of the machine, is supported in several bearings 27, secured to the top surface of base 3. At one of the ends of shaft 26 is a handwheel 28.

The two movable pillow-blocks 5 are each supported by two vertically arranged screws 30 which are similar to screws 19 and held in suitable bosses 31 of base 3 in the same manner as the screws 19. Worm-wheels 32, secured to the upper shank part of each screw 30, are engaged and rotatable by means of worms 33, also fast to shaft 26. Worms 33 differ from worm 25 in that the latter is threaded opposite to the other worms 33 so that when turning handwheel 28 in one direction, the straightening rolls 7 will be raised on their pillow-blocks 5, while the pivot rolls 15 are being lowered, as shown in Fig. 14. If handwheel 28 should be turned in the opposite direction, pivot rolls 15 will be raised, while pillow-blocks 5 are being lowered (Fig. 16).

The pitch of thread of either set of screws 19, 30, or the ratio of gearing of worm-wheel devices 33, 32 and 25, 24 may differ so that one set of rolls moving in one direction may travel faster than the other which is moved in the opposite direction. Said pitch of thread of screws and ratio of gearing of worm-wheel devices may be the same on both sets of screws and on both worm-wheel devices. In this event, screws 19 travel as fast as screws 30, but in opposite direction. By means of handwheel 28 the lower rolls are moved a definite amount relative to each other. The lengths of the respective movements of both sets of screws depend on the proportionate length of straightening rolls 7 and supporting rolls 11 (see diagrammatic views).

Rolls which are adjusted relative to each other are depicted in Fig. 16, where the pivot rolls 15 have lifted the supporting rolls 11 from their bearing supports and where the supporting rolls in turn have lifted and sustained the straightening rolls 7 on their working surfaces, while pillow-blocks 5 have been lowered.

The upper section 2 of the straightening machine comprises a rigid frame 35 within which is supported at its outer ends a row of upper sheet-flexing elements or straightening rolls 37 arranged in staggered relation with respect to the lower straightening rolls 7. Between these two sets of straightening rolls or sheet-flexing elements the sheet or plate to be straightened is passed.

The upper rolls 37 are rigidly supported against pressure by upper supporting rolls 38, rotatable in frame 2. These rolls may be divided in any desirable number of sections to increase their stiffness and prevent flexing, so that rolls 37 will be supported in accordance thereto. Frame 35, as usual, may be raised, lowered or tilted by means of the two handwheels 39, rotatable shafts 40 of which each possesses two worms 41, engaging worm-wheels 42. The latter are fast to threaded, vertically placed spindles 43, held rotatable in the four corners of the frame to engage a thread each

in the uprights 4 of lower section 1. The weight of frame 35 is counterbalanced by means of helical springs 44 on spindles 43. Every roll of both sets of upper and lower straightening rolls is provided at one of its ends with a universal coupling 45, Fig. 1, connected to driving shafts 46 which are rotated by a suitable transmission device (not shown). The constructions shown for adjustment of upper frame section 2 relative to lower frame 1 by means of the two handwheels 39 and related mechanism is known in the art and may be replaced by any other known adjusting device.

Construction of Figs. 1, 2, 5 as well as Figs. 6, 7, 9, 10 and 11 hereinafter described show the rolls 15 in straight, non-deflected position, touching each other over their respective entire length and this location shall be referred to as the neutral location of these rolls. The location of their respective bearings and supports as shown in the above mentioned figures shall also be referred to as their neutral location as long as these elements are not displaced in vertical directions. To follow the deflections of the rolls, a tilting movement alone does not constitute a change in the neutral locations of the bearings. Consequently, bearing blocks 12 in both Figs. 14 and 15 should be considered in neutral locations under the meaning of the term used herein.

Fig. 7 illustrates a lower body section 1' which in its structural features is similar to that previously described and in which like parts have received like numerals with a prime mark attached to each such numeral. Worm-wheels 24' and their worm 25' which actuate yoke 11' are however displaced and located underneath the upper surface of base 3'. Worm 25' is mounted on a separate shaft 48 in bearings 49, Fig. 8, and is provided with a suitable handwheel 50 located on the same side as handwheel 28'. A rotation of handwheel 50 will raise or lower the lower supporting rolls in the manner described before. It is thus possible for an operator to adjust both the straightening rolls and the pivot rolls independent of each other and obtain the same or similar displacement of rolls as those shown in the diagrammatic views of Figs. 14 and 16.

Fig. 6 illustrates a lower base section 1'', which, with the exception of the roll adjustment, is identical to lower body section 1 shown in Fig. 1. Therefore, those parts of Fig. 6 which are alike and similar to those of Fig. 1 have received like numerals with two prime marks attached to same to eliminate a lengthy description and make its reading simple and more comprehensible.

The roll adjustment differs from that of Fig. 1 in that the pivot rolls 15'' are held in a stationary bearing support 17''. Furthermore, pillow-blocks 13'' of supporting rolls 11'' may be raised and lowered by means of worms and worm-wheels 25'', 24'', and screws 21''. The arrangements of these devices are similar to those which raise and lower the straightening rolls 7'' described and shown in more detail in Fig. 2. However, worms 25'' are threaded in the same direction as worms 33'' so that pillow-blocks 13'' and 5'' will travel in the same direction, when handwheel 28'' is rotated.

Straightening rolls 7'' are longer than supporting rolls 11'' which are symmetrically arranged in respect to rolls 7''. As both sets of rolls 7'' and 11'' are deflected into similar curves (Fig. 19), it is evident that the length of travel of pillow-blocks 13'' must be shorter than that of blocks 5'' (Fig. 18).

The amount of travel of supports 5" and 13" may be varied by selecting for instance a different ratio of gearing for respective worm-wheel devices 33", 32", and 25", 24".

If desired, worms 25" may be attached to a separate shaft and separate adjustments provided for straightening rolls and supporting rolls similarly as described in connection with Fig. 7.

Fig. 9 illustrates a lower section 101, wherein two sets of supporting rolls 111 are employed and the formerly described pivot rolls eliminated. Both sets of rolls 111 are held at their outer ends in stationary bearing supports 113 and at the middle of section 101 in an adjustable bearing support 117, Fig. 11, guided in uprights in the manner previously shown and described.

To shaft 126 is fastened a worm 125 which engages two worm-wheels 124, fast on screws 119. The latter are identical to screws 19 of Fig. 1. The outer and inner ends of both sets of rolls 111 are rotatable in respective swivel blocks or bearing bodies 112, 114 with curvilinear bearing surfaces similar to those already described.

Bearing blocks 105 supporting the lower straightening rolls 107 in swivel blocks 106 are raised or lowered by means of screws 130 in opposite direction to bearing support 117.

A diagrammatical view of the displacement or rolls 107, 111, is disclosed in Fig. 20, showing the straightening rolls 107 raised by means of the supporting rolls 111, while bearing supports 105 are shown in a lowered position relative to their neutral location. It is thereby indicated that the bearing bodies 114 of supporting rolls 111 and bearing supports 105 travel in opposite directions.

In Figs. 9 and 11 those parts which are identical or similar to those in Fig. 1 have received like numerals with a 1 or 10 attached in front of the respective tens or unit numbers thereof, so as to facilitate the reading of the drawings and simplify the description thereof.

If desired, bearing block 117 may also be raised or lowered by means of a separate shaft attachment in the manner shown in Fig. 7.

Fig. 10 is similar to Fig. 9, the difference between the two is the same as that between the two respective Figs. 6 and 1, wherein the latter has the supporting block or yoke 17 movable and the other stationary. In Fig. 10 the outer pillow-blocks 113' of supporting rolls 111' are made adjustable, the constructional features being identical to those described and shown in Fig. 6 and need therefore no further description. The adjustment of straightening rolls and supporting rolls relative to each other is in the same direction, however differing as to amount, in the same manner and for the same reason as described in connection with Fig. 6.

In Fig. 10 like parts identical and similar to those shown in Figs. 9 and 11 have received like numerals with a prime mark attached to same.

Two independent adjustment shafts similar in construction to those shown in Fig. 7 may of course also be employed, if so desired.

A diagrammatic view of one of the adjustments possible with the construction of Fig. 10 is shown in Fig. 22.

Upper frame 2 with upper straightening rolls 37 and supporting rolls 38, Figs. 1 and 2, is adjustable in such a way with respect to lower frame 1 that the first rolls on the entry side of the machine can be set deeper than the following ones. Thereby, the sheet is subjected to deep corrugations on the entry side of the machine and these deep bends are gradually removed by

the succeeding rolls until the sheet emerges from the machine in flat condition. Fig. 2 shows the upper frame adjusted for feeding the sheets from right to left as indicated by the arrow.

Perspective view of Fig. 24 shows part of a typical formation of transverse corrugations to which a sheet is subjected by a convex roll formation. Those waves designated by numerals 78, 79, Fig. 24, which are in contact with deflected rolls 77 follow the convex contours of said rolls 10 and, consequently, waves of differing transverse amplitude are formed in the sheet by the deflected rolls 77. It will be noted that by reason of the convex contour of lower rolls 77, the middle section 79 of the waves is subjected to a deeper 15 bend than the ends 78 of these waves. This deeper bend causes a greater pressure along this area which results in a stretching action along the middle area of the sheet.

It is evident that the transverse amplitude of 20 the waves or corrugations, formed by straightening rolls which are deflected into a concave contour, will be reversed. The ends of the sheet will have deeper bends than the middle part of the sheet. Consequently, the ends of the sheets will 25 be subjected to a stretching action.

Fig. 24 may represent, for instance, a condition as that shown in Fig. 17. This construction permits adjustments of straightening rolls 7 and pivot-rolls 15 in opposite vertical directions to 30 place elements 7 and 15 into new positions relative to each other, so as to deflect both rolls 11 and 7 into the desired working contours. Supporting blocks 13, which sustain supporting rolls 11 at their ends, are maintained in neutral locations 35 regardless of any adjustments of straightening rolls 7 and pivot-rolls 15. It is therefore obvious, that those sections of the waves of differing transverse amplitude which are located in the same vertical planes as supporting blocks 13 will be maintained in neutral locations, while a sheet is flexed between the straightening rolls, regardless of whether the middle sections of said waves are being raised, while the edge sections thereof are being lowered, or vice versa.

The neutral, straight location of the rolls and their supports previously referred to, may be utilized to pass through a sheet for finishing same with even pressure and therefore without stretching any particular areas of the sheet.

Each of the machines shown in Figs. 1, 6, 7, 9, 10, permits concave as well as convex roll formations. Both concave and convex formations have been shown for machines in Figs. 1 and 7 in the diagrammatic views of Figs. 14, 15, 16, 17, while one characteristic roll formation each has been illustrated for the others to show clearly the adjustments and movements of the rolls and their supporting means relative to each other.

In Figs. 14 to 23, the rolls are illustrated to be in the same vertical plane. The sheets are depicted to follow the contours of the lower, deflected straightening rolls. The diagrammatic views show the adjusted and deflected condition of the rolls and that of their supports in exaggerated form to more clearly demonstrate the movements of the rolls relative to each other and their bearing supports. In actuality, these movements are very short and hardly ever exceed a small fraction of one inch. Arrows indicate the relative adjustments. Furthermore, the exaggerated form of the deflected lower straightening rolls shows clearly which areas of the sheet are subjected to the greatest pressure.

In Fig. 14 which discloses one adjustment of 75

rolls possible with the machines of Figs. 1 and 7, the lower straightening roll 7 is shown to be raised relative to supporting roll 11, while pivot roll 15 is lowered relative to the latter. Therefore, the rolls are illustrated to be adjusted in such a manner that the working surfaces of the lower three rolls are not in contact with each other. When a sheet, of which its two edge areas are shorter than its middle part, is being passed between the 10 two straightening rolls 31, 7, the rolls 7 and 11 will assume a concave formation (Fig. 15), causing the greatest pressure at the edge areas and thus produce a result which is known to straighten a sheet of such distorted shape most effectively. It will be noted that on account of the curvilinear supporting surfaces of the bearing bodies 6 and 12, these bearing bodies are free to follow the movement of the flexed rolls and thus relieve unnecessary strains on the bearing 15 ends of the rolls, reducing wear and giving longer life to same.

Another roll adjustment possible with the machines of Figs. 1 and 7 is shown in Figs. 16 and 17. The pivot rolls 15 were described to move in opposite direction to the movement of pillow-blocks 5 of the straightening rolls. For this reason, the upward movement of the pivot rolls 15 causes the supporting rolls 11 to be lifted from their bearing supports 13; the straightening rolls 7 are also raised on their working surfaces in accordance therewith, while the pillow-blocks 5 are being lowered relative to their neutral location. A displacement of rolls of this character is required for the straightening of sheets, of which the two edge areas are longer and which require maximum pressure at the middle part of the sheet.

Fig. 17 discloses both the straightening rolls and the supporting rolls flexed into a convex contour with the pressure for stretching applied in the middle of the sheet.

Fig. 18 illustrates a diagrammatic view of an adjustment of the straightening rolls 7" and supporting rolls 11" made possible by means of the mechanism of Fig. 6. Both sets of rolls 7" and 11" are being raised, while the pivot rolls 15" remain stationary. A sheet passing through the rolls will flex the raised rolls into a concave contour, Fig. 19, which therefore discloses a view which is similar to Fig. 15.

The respective convex roll formation possible with mechanism of Fig. 6 would be similar to Figs. 16 and 17, the difference being that pillow-blocks 5" and 13" are both lowered different amounts, while yoke 17" remains stationary.

Figs. 15, 17, 19, show the lower straightening rolls and their supporting rolls in flexed working position and it will be noted that the flexed straightening rolls rest on the similarly flexed supporting rolls over the entire length of the latter.

The adjustment of rolls illustrated in the diagrammatic view of Fig. 20 is made possible by means of the construction shown in Fig. 9. The inner bearing bodies 114 of supporting rolls 111 are raised relative to their outer bearings 112, causing the straightening rolls 107 to be lifted from their pillow-blocks 105. At the same time pillow-blocks 105 of the lower straightening rolls 107 are lowered so that the straightening rolls 107 may be enabled to assume the desired flexed contour when a sheet is passed through the rolls. The divided supporting rolls 111 assume an inverted V shape as shown.

When forming a concave straightening roll 75 curve with the construction disclosed in Fig. 9, the

movements of lower rolls and their supports would be similar to Figs. 14 and 15, with the difference that the divided supporting rolls 111 would form a V shape similar to that shown in Fig. 23.

In the diagrammatic view of Fig. 22, the straightening rolls 107 and the outer bearings 112 of supporting rolls 111 are made adjustable, as disclosed in the constructional view of Fig. 10. While the straightening rolls 107 are raised on their pillow-blocks 105, the outer bearings 112 of supporting rolls 111 are also being raised relative to their inner bearings 114, causing thereby a V formation. This is similar to Fig. 6, in connection with which the relative 15 adjustments of straightening rolls and supporting rolls have been described. Consequently, similar as in Fig. 6, the pillow-blocks 105, Fig. 22, will travel faster than the outer bearings 112 of supporting rolls. A sheet passing through the 20 rolls, Fig. 23, will therefore flex the lower straightening rolls into a concave formation.

The corresponding convex straightening roll formation possible with mechanism of Fig. 10, requires movements of lower rolls and their supports identical to those described in connection with the convex roll formation possible with the construction shown in Fig. 6, with the difference that divided supporting rolls 111 form an inverted V shape similar to that shown in Fig. 21. 30

While in the various modifications disclosed, the result will either be a concave or convex formation of the rolls, it has been found necessary to disclose various possibilities of producing similar results by different arrangements of mechanism, so as to enable the applicant to select either one of the various constructions, which all embody the relative adjustment of straightening rolls and supporting instrumentalities, to suit his purpose. 40

It will be understood that the liftable bearing arrangement for the straightening rolls and supporting rolls, distinctly noticeable in Figs. 16 and 20, represents a novel feature which is independent of adjustments of straightening rolls and supporting means relative to each other to deflect the straightening rolls into the desired working contour. Bearing arrangement in locked condition as illustrated in Fig. 12 or any of the bearings used heretofore may be employed for these rolls. Lifted rolls as shown in Figs. 16 and 20, for instance, would then be eliminated and the deflected roll contours as shown in Figs. 17 and 21 would be positively produced by the adjustment proper and not by the sheet passing between the straightening rolls. 55

The modification of the bearing arrangement for straightening and/or supporting rolls, illustrated in Figs. 12 and 13, comprises a supporting or pillow block 55. The bearing body 56, within which the ends of rolls 57 are supported, as well as the pillow block 55 may be provided with curvilinear contact surfaces as shown in the other designs. In addition to that, bearing body 56 possesses two spherical contact faces at its outer ends 58 which contact faces engage curvilinear or spherical supports 60 which allow the bearing body to follow the movement caused by a flexure of the rolls. The lower parts 61 of said supports are vertically movable in recesses of supporting block 55 and guided by means of suitable gibbs or plates 62. Lower parts 61 are provided with means for locking same to pillow block 55 by means of keys 63 passing through these parts and into the pillow block. When desired to 70

permit bearing body 56 to move in vertical directions with relation to pillow block 55, keys 59 may be removed. To the lower surface of each bearing end 58 are fastened guide plates 63 which serve the purpose to prevent the bearing block 56 from being raised and moved away from its supports 60. This may be the case under conditions shown in the diagrammatic views of Figs. 16, 17, 20, 21. It will be noted that the line through both centers of spherical supports 60 passes through the fulcrums of the rolls. The fulcrums of curvilinear bearing surfaces of bearing bodies 56 are also in alignment with the other fulcrums. For this reason, deflection of the rolls will cause the smallest possible dislocation of the bearing body 56 which will result in less strain and comparatively little wear on the rolls.

If keys 59 are inserted into this bearing arrangement, the rolls are positively deflected into a convex contour, whenever the straightening rolls and supporting means are subjected to a corresponding relative adjustment. This means that the rolls are prevented from being lifted from their pillow-blocks and bearing supports and they can not assume positions shown in Figs. 16 and 20.

Figs. 12 and 13 therefore show a design which permits two different methods of operation. This has been found desirable so as to increase the range of application, especially when very thin sheets are to be straightened on a machine which has been primarily designed for heavier sheets with correspondingly larger roll diameters, which would not permit deflection when processing a thin sheet.

It will be understood that the constructions of the sheet straightening machines shown, may be modified in a number of ways without departing from the spirit of the invention. Thus relative adjustments of straightening rolls and supporting means may either be arranged for the lower rolls as shown, or for the upper rolls, or for both lower and upper rolls; or pivot rolls may be eliminated in connection with the constructions shown in Figs. 1, 6, and 7 and roll rests employed instead of same, retaining however the relative adjustment of straightening rolls and such reinforcing means.

As the various constructions disclosed are susceptible to a number of other modifications without departing from the spirit of the present invention, the scope of the invention is to be restricted only by the limitations contained in the appended claims.

55 I claim:

1. In roller leveler mechanisms, sets of straightening rolls between which a distorted sheet is to pass, supporting means to back up the straightening rolls on their working surfaces, reinforcing elements to sustain one set of said supporting means and further means to regulate the reinforced set of supporting means and its related straightening rolls relative to each other.

2. In roller leveler mechanisms, sets of straightening rolls between which a distorted sheet is to pass, supporting means to back up the straightening rolls on their working surfaces, reinforcing elements to sustain one set of said supporting means and further means to regulate the reinforcing elements and their related straightening rolls relative to each other.

3. In roller leveler mechanisms, sets of straightening rolls between which a distorted sheet is to pass, supporting means to back up the straightening rolls on their working surfaces, means to

regulate one set of rolls and its supporting means relative to each other, and liftable bearing bodies at the ends of said straightening rolls to follow the movement of the rolls.

4. In roller leveler mechanisms, sets of straightening rolls between which a distorted sheet is to pass, supporting rolls to back up the straightening rolls on their working surfaces, means to regulate one set of straightening rolls and its supporting rolls relative to each other, and liftable bearing bodies at the ends of both said adjustable rolls to follow the movements of the rolls.

5. In roller leveler mechanisms, sets of straightening rolls between which a distorted sheet is to pass, supporting means to back up the straightening rolls, bearing supports to sustain one set of straightening rolls, means to lift said set of straightening rolls from said bearing supports and further means to lower said bearing supports.

6. In roller leveler mechanisms, sets of straightening rolls between which a distorted sheet is to pass, supporting rolls to back up the straightening rolls on their working surfaces, bearings to sustain said rolls at their ends, bearing supports to sustain bearings of one set of straightening rolls and related supporting rolls, means to lift said set of straightening rolls and related supporting rolls from said bearing supports and further means to lower the bearing supports of the liftable straightening rolls while the latter are being lifted.

7. In roller leveler mechanisms, sets of straightening rolls between which a distorted sheet is to pass, supporting rolls to back up the straightening rolls on their working surfaces, bearings to sustain both said rolls at their ends, bearing supports to sustain the bearings of one set of straightening rolls and related supporting rolls, means to sustain said set of straightening rolls and related supporting rolls and further means to lower said bearing supports of both said rolls relative to each other.

8. In combination with roller lever mechanisms, straightening rolls and supporting rolls, bearing elements to sustain said rolls at their ends, supporting means to carry said bearing elements, means movably guiding said bearing elements with relation to said supporting means in vertical directions.

9. In combination with roller leveler mechanisms, straightening rolls, bearing elements to sustain said rolls at their ends, supporting means to carry said bearing elements, means movably guiding said bearing bodies in vertical directions with relation to said supporting means and further means to lock said bearing elements and supporting means against a vertical movement.

10. In combination with roller leveler mechanisms, straightening rolls and supporting rolls, bearing bodies, curvilinear sliding surfaces thereon to sustain said rolls, supporting-blocks, curvilinear surfaces thereon to oscillatably carry said bearing bodies, the fulcrums of said bearing bodies and those of the rolls to be in substantial alignment, and means movably guiding said bearing bodies in vertical directions with relation to said supporting-blocks.

11. In combination with roller leveler mechanisms, straightening rolls and supporting rolls, bearing bodies to sustain said rolls, curvilinear bearing supports to oscillatably support said bearing bodies, supporting-blocks to sustain said bearing supports, means movably guiding said curvilinear bearing supports in either one of two

- vertical directions with relation to said supporting-blocks, the fulcrums of said curvilinear bearing supports and those of the rolls being in substantial alignment.
- 5 12. In combination with roller leveler mechanisms, straightening rolls and supporting rolls, bearing bodies to sustain said rolls at their ends, curvilinear bearing supports to oscillatably support said bearing bodies, supporting-blocks to 10 carry said bearing supports, means movably guiding said curvilinear bearing supports in vertical directions with relation to their supporting-blocks and further means to lock said curvilinear bearing supports and supporting-blocks against 15 a vertical movement, the fulcrums of the curvilinear bearing supports and those of the rolls being in substantial alignment.
- 10 13. In combination with mechanisms of the character described, straightening rolls, supporting rolls for same, bearing bodies to sustain said supporting rolls at their ends, supporting blocks to carry said bearing bodies, means movably guiding said bearing bodies in vertical directions with relation to said supporting blocks.
- 15 14. In mechanisms of the character described, straightening rolls, supporting means to reinforce said straightening rolls substantially in their middle and at locations away therefrom, means to regulate said supporting means in the 20 middle of the straightening rolls in one vertical direction and to regulate the related straightening rolls in opposite direction, further means to maintain said supporting means at locations away from the middle of the straightening rolls 25 in neutral position.
- 20 15. In mechanisms of the character described, straightening rolls, supporting means to reinforce said straightening rolls substantially in their middle and at locations away therefrom, means 30 to regulate said supporting means at locations away from the middle of the straightening rolls in vertical directions and to regulate the related straightening rolls in identical directions relatively thereto in such a manner that said straightening rolls are displaced greater distances 35 from their neutral locations than said supporting means located away from their middle, further means to maintain said supporting means located substantially in the middle in neutral position.
- 25 16. In mechanisms of the character described, two rows of straightening rolls, each row adapted 40 to engage one surface of a sheet to be flattened, means to regulate said two rows of straightening rolls toward and away from each other to position 45 said rows of rolls to repeatedly flex a sheet passed between them, backing means for said rows of straightening rolls, and auxiliary means which afford 50 adjustments of straightening rolls and their related backing means relative to each other in order to deflect said rolls for stretching short sections of the sheet.
- 30 17. In mechanisms of the character described, two rows of straightening rolls, each row adapted 55 to engage one surface of a sheet to be flattened, means to regulate said two rows of straightening rolls toward and away from each other to position 60 said rows of rolls to repeatedly flex a sheet passed between them, backing means for said rows of straightening rolls, and auxiliary means which afford 65 adjustments of straightening rolls and their related backing means relative to each other in identical directions in order to deflect said rolls for stretching short sections of the sheet.
- 35 18. A supporting mechanism for backing deflected straightening rolls in roller levelers comprising in combination with straightening rolls positioned to repeatedly flex a sheet passed between them, one-piece supporting rolls to reinforce said straightening rolls when deflected, and adjustable means arranged along said supporting rolls adapted to travel toward and away from 10 said supporting rolls to deflect said supporting rolls into contours similar to those of said deflected straightening rolls.
- 40 19. A supporting mechanism for backing deflected straightening rolls in roller levelers comprising in combination with straightening rolls positioned to repeatedly flex a sheet passed between them, one-piece supporting rolls to back 15 said straightening rolls when deflected, bearings to sustain the ends of said supporting rolls, reinforcing means for said supporting rolls, further means adapted to raise or lower the ends of said 20 supporting rolls relative to said reinforcing means in order to deflect said supporting rolls into contours similar to those of said deflected straightening rolls.
- 45 20. In mechanisms of the character described, straightening rolls positioned to repeatedly flex a sheet passed between them, supporting means to back said straightening rolls when deflected, reinforcing means arranged along said supporting means adapted to travel toward and away from 25 said supporting means and to respectively deflect said supporting means and the related straightening rolls or permit both to be deflected by the sheet passed between said rolls, said deflected straightening rolls engaging the related supporting 30 means substantially along the entire length of the latter.
- 50 21. In mechanisms of the character described, straightening rolls positioned to repeatedly flex a sheet passed between them, supporting means to back 35 said straightening rolls, adjustable means to regulate said straightening rolls from neutral locations in either one of two directions, further adjustable means adapted to displace the related supporting means toward or away from said adjusted straightening rolls and to respectively deflect said straightening rolls or permit them to be deflected by the sheet passed therebetween, and common means to actuate both said adjustable means simultaneously.
- 55 22. In mechanisms of the character described, straightening rolls positioned to repeatedly flex a sheet passed between them, supporting means to back 40 said straightening rolls, independently-operable means to adjust straightening rolls from neutral locations in either one of two directions, further independently-operable means to adjust 45 the related supporting means relative to said adjusted straightening rolls, said supporting means being so displaced relative to the related straightening rolls that said supporting means will back 50 said rolls when the latter are deflected.
- 60 23. In mechanisms of the character described, straightening rolls positioned to repeatedly flex a sheet passed between them, supporting means arranged therealong adapted to maintain neutral 55 locations, supplementary adjustable supporting means for said straightening rolls, means adapted to regulate said adjustable supporting means in either one of two vertical directions and to regulate 65 the related straightening rolls in opposite direction thereto in such a manner that said straightening rolls and related adjustable supporting means are displaced substantially equal 70 distances from their respective neutral locations.
- 65 75

24. In mechanisms of the character described, straightening rolls positioned to repeatedly flex a sheet passed between them, supporting means arranged therealong adapted to maintain neutral locations, supplementary adjustable supporting means for said straightening rolls, means adapted to regulate said adjustable supporting means in one direction and to regulate the related straightening rolls in opposite direction thereto in such a manner that the length of adjustment of said adjustable supporting means is different from the length of adjustment of said related straightening rolls.
25. In mechanisms of the character described, straightening rolls positioned to repeatedly flex a sheet passed between them, means to regulate straightening rolls in either one of two vertical directions for a deflection of said rolls, supporting means for said straightening rolls, means to maintain said supporting means in neutral locations, supplementary adjustable backing means for said straightening rolls adapted to perform equal lengths of travel each in vertical directions and to position said adjustable backing means with respect to said supporting means in such a manner that both said backing means and said supporting means will reinforce the related straightening rolls when the latter are deflected.
26. In mechanisms of the character described, rows of straightening rolls, means to adjust said rows of straightening rolls toward and away from each other to position said rows of rolls to repeatedly flex a sheet passed between them, supporting means for one set of said straightening rolls adapted to maintain neutral locations, supplementary adjustable backing means for said set of straightening rolls, and auxiliary adjusting means to displace said adjustable backing means and their related straightening rolls in identical vertical directions in such a manner that said displacement of said rolls is always greater than said displacement of said related backing means.
27. In mechanisms of the character described, straightening rolls, two rows of supporting rolls arranged therealong to back said straightening rolls, means to maintain the outside ends of said rows of supporting rolls in neutral locations, further means to regulate adjacent ends of said rows of supporting rolls in either one of two vertical directions and to regulate the related straightening rolls in opposite direction thereto.
28. In mechanisms of the character described, straightening rolls, two rows of supporting rolls to back said straightening rolls, means to maintain adjacent ends of said rows of supporting rolls in neutral locations, further means to regulate the outside ends of said rows of supporting rolls in either one of two vertical directions and to regulate the related straightening rolls in identical vertical direction relatively thereto.
29. In mechanisms of the character described, straightening rolls positioned to flex a work sheet passed between them, backing means located in- intermediate the ends of said straightening rolls, adjustable means to regulate said straightening rolls toward or away from the work sheet, and auxiliary means to regulate their respective backing means in opposite directions thereto to deflect said straightening rolls to stretch short sections of the work sheet.
30. In mechanisms of the character described, straightening rolls positioned to flex a work sheet passed between them, backing means for said straightening rolls adapted to maintain neutral locations, reinforcing means for said straightening rolls, said backing means and said reinforcing means being arranged along said straightening rolls intermediate their ends, and means which afford adjustments of said straightening rolls and their related reinforcing means relative to each other and relative to said neutral backing means for a deflection of said straightening rolls.
31. In mechanisms of the character described, in combination with straightening rolls, one-piece supporting rolls to reinforce said straightening rolls, bearings for both of said rolls at their ends, and means including said bearings and adjustable elements, whereby said straightening rolls and said supporting rolls are deflectable into substantially identical working contours by a sheet moving between said straightening rolls.
32. The method of straightening sheets in roller levelers which comprises subjecting a sheet to waves or corrugations of differing transverse amplitude to stretch short sections of said sheet, raising the middle sections of said waves of differing transverse amplitude and lowering the edge sections of each such raised wave.
33. The method of straightening sheets in roller levelers which comprises subjecting a sheet to waves or corrugations of differing transverse amplitude to stretch short sections of said sheet, lowering the middle sections of said waves of differing transverse amplitude and raising the edge sections of each such lowered wave.
34. In the method of roller leveling sheets by subjecting said sheets to waves or corrugations of differing transverse amplitude to stretch short sections of said sheets, the steps which comprise raising the middle sections of said waves of differing transverse amplitude, maintaining in neutral locations sections of said waves which are away from said middle sections, and lowering the edge sections of said waves of differing transverse amplitude.
35. In the method of roller leveling sheets by subjecting said sheets to waves or corrugations of differing transverse amplitude to stretch short sections of said sheets, the steps which comprise lowering the middle sections of said waves of differing transverse amplitude, maintaining in neutral locations sections of said waves which are away from said middle sections, and raising the edge sections of said waves of differing transverse amplitude.

FRIEDRICH K. MÄUSSNEST.
